UNITED STATES PATENT OFFICE.

ROBERT HOLLINGWORTH, OF HAMILTON, ONTARIO, CANADA.

PORTABLE WHEELED TOY.

1,090,308.

Specification of Letters Patent. Patented Mar. 17, 1914.

Application filed August 27, 1912, Serial No. 717,327. Renewed September 18, 1913. Serial No. 790,568.

To all whom it may concern:

Be it known that I, ROBERT HOLLINGWORTH, a subject of the King of Great Britain, residing at Hamilton, in the Province of Ontario and Dominion of Canada, have invented new and useful Improvements in Portable Wheeled Toys, of which the following is a specification.

This invention relates to portable wheeled toys and has for an object to provide musical sounding devices which will be operated as the toy is propelled.

A still further object of the invention is to provide a toy with different groups of musical sound producing devices and means whereby one or more of the different groups of devices may be only sounded at intervals so that the sounds emanating from the different devices will be permitted to commingle with or blend into the sounds emanating from the other devices and thereby enlarge the tone range of the toy and render it extremely pleasing and satisfying to the ear.

In the drawing forming a portion of this application, and in which like letters of reference indicate similar parts in the several views:—Figure 1 is a longitudinal section through the toy. Fig. 2 is a top plan view thereof. Fig. 3 is a rear end view of the same. Fig. 4 is a section through a portion of the toy showing the shaking position of the knocking arm. Fig. 5 is a view similar to Fig. 1 showing a slightly modified form of the invention. Fig. 6 is a perspective view of one of the spring arms.

With particular reference to Figs. 1 to 4 inclusive and Fig. 6 it is said that the toy comprises a rectangular portable supporting frame which includes parallel spaced side bars 1 and connecting horizontal front and rear bars 2 and 3. Bearing brackets 4 at the rear of the supporting frame are designed to revolvably support an axle 5 on which ground engaging wheels 6 are mounted. Similar bearing brackets 7 are mounted upon the supporting frame near the front end thereof to receive a suitable axle 8 on which other ground wheels 9 are secured. At the front of the supporting frame is attached a tongue 10 whereby the toy can be propelled manually and actuated to impart movements to the different sound carrying devices to be hereinafter explained.

The front and rear rollers 11 and 12 are journaled at their ends in the side bars 1 of

the supporting frame. Passing over these rollers are endless belts 13 to which bell or like sounding devices 14 are secured. The belts 13 are spaced relatively and disposed therebetween and mounted preferably on the rear axle 12 is a gear wheel 15 which meshes with a similar driving gear wheel 16 upon the axle 5 so that as the toy is propelled over the ground movements will be imparted to the belts to shake or agitate the sound devices. At the rear of the supporting frame is a flexible member 17, the opposite ends of the same being secured preferably at 18 to the end bar 3. Said member 17 has secured thereto on its underside bells or suitable sound devices 19 which are similar to the devices 14 but of a different tone. The central portion of the member 17 is provided with a loop 20 into which the arm 21 of a bell crank lever 22 extends. The lever is pivoted upon the supporting frame of the structure and located immediately at the rear of the axle 5. The arm 23 of the lever extends downwardly and rearwardly and provided directly opposite the axle 5 with a wiping surface 24. A spring 25 on the supporting frame is operatively connected with the bell crank lever, exerting its pressure thereagainst so as to normally sustain the member 17 in one position. A radial knocking arm 26 extends from the axle 5, being provided with a substantially spherical outer extremity 27 which is adapted to ride across the wiping surface 24 of the bell-crank lever and to rock said lever whereby the member 17 will be moved from its normal sustained position and agitated to sound the devices 19.

Pedestals or like supporting devices 27 rise from the corners of the portable supporting frame. These pedestals are preferably constructed of springy wire, each being provided with an intermediate coiled portion 28 whereby it is rendered extremely sensitive to vibration of the toy. Caps 29 are secured to the upper ends of the pedestals and as shown each cap is provided with arms 30 which are curved upwardly and then outwardly and then downwardly and terminally connected with bells or sounding devices 31. A vertical arm 32 of the cap supports a similar sounding device 33.

Now that the details of construction of the toy are described it is said that when the device is propelled across any suitable surface that may be found desirable to produce the

desired result, motion will be imparted to the sounding devices 14 and 19. In other words there will be times when the devices 14 and 19 will be sounded together and then 5 other times when they will be only sounded in certain order of adjustment of the axle 5. The devices 31 and 33 on the corner pedestals will be almost continually sounded, however this may depend upon the amount 10 of vibration imparted to the toy as the latter is propelled. The different sounds emanating from the respective devices 14, 19, 31, and 33 blend into and are made to harmonize with each other so that an extremely 15 pleasing effect is produced.

In the modified form of the invention shown in Fig. 5 the portable supporting frame of the structure has its side bars 1^a slidably supporting a reciprocatory member 20 34. A spring 35 on the frame bears against the member 34 so as to move the latter in one direction and in rapid order. The member 34 supports sound devices 14^a which are similar to the devices 14. A driving axle 5^a 25 has a mutilated gear 36 thereon which is adapted to mesh at certain intervals with a rack section 37 on the reciprocatory platform or member 34 so that as the axle is revolved motion will be imparted to the member against the resistance of the spring 35. 30

Shaking the member 34 in the manner described causes the devices 14^a to be properly sounded.

I claim:—

1. A toy comprising a wheeled frame, an 35 endless belt carried thereby, means for moving the belt, sound producing devices carried by the belt, a flexible member carried by the frame and provided with sound producing devices, a vibrator connected with said flexible member and means operated by the belt driving means to operate said vibrator. 40

2. A sounding toy comprising a wheeled frame, spaced rollers carried thereby, an endless belt passing over the rollers, said 45 frame including a driving axle, gearing between the driving axle and one of the rollers, sound producing devices carried by the belt, a flexible member, sound producing devices carried by said member, a vibrator supported by the frame and connected with the flexible member and means on the driving axle 50 for operating the vibrator.

In testimony whereof I affix my signature in presence of two witnesses.

ROBERT HOLLINGWORTH.
